UNITED STATES PATENT OFFICE.

FREDERICK GEORGE WINKLER, OF BUFFALO, NEW YORK, ASSIGNOR, BY MESNE ASSIGNMENTS, TO BEREND J. BURNS AND CLIFFORD A. CUTLER, BOTH OF BUFFALO, NEW YORK.

SPRING.

1,096,582.

Specification of Letters Patent. Patented May 12, 1914.

Application filed November 1, 1907. Serial No. 400,252.

To all whom it may concern:

Be it known that I, FREDERICK GEORGE WINKLER, a citizen of the United States, residing at Buffalo, county of Erie, and State 5 of New York, have invented certain new and useful Improvements in Springs, of which the following is a full, clear, and exact description.

My invention relates generally to springs 10 which may be used in most places where springs are in use to-day.

My chief object in producing the invention herein described has been to provide means whereby a spring will carry a tare 15 weight (*i. e.*, the initial deadweight load) which is much greater than the subsequently added load and at the same time have the following characteristics.

My invention provides means whereby, 20 when the tare weight load is carried by the spring, the spring will offer a resisting power against such load which progresses in a substantially arithmetical progression.

When a comparatively small additional load 25 is added the spring will continue to offer a resisting power to that load which still increases in a substantially arithmetical progression. When the said tare weight and the added varying load have placed the spring 30 under elastic strain then the further compressive action of the spring which may be called into play, as for example, by violent shocks caused by the passage of the vehicle equipped with my spring over any unevenness or obstacles in its path, it will respond 35 and offer a resisting power to such shocks which will increase in a substantially geometrical progression. Moreover I so construct my spring that the final resisting power of 40 it is so great that in actual use it will never be compressed to its final possible point of compressive action.

In my drawings and specification I have shown several forms of my spring as particularly adapted to be used in motor vehicles but it will be readily seen that some or all forms of the spring herein shown and described can be used in a great variety of ways and I do not confine myself to the particular adaptation of the spring to motor vehicles as herein shown and described.

Referring now to the accompanying drawings in which like characters of reference 55 refer to corresponding parts throughout the several figures; Figure 1 is a side view show-

ing the several unassembled parts of one of my springs. Fig. 2 shows a similar view of the several parts of the same spring as when assembled. Fig. 3 shows a similar view of the several assembled parts of the same 60 spring at a point of compression when the change of resisting power from the arithmetical to the geometrical progression occurs. Fig. 4 shows a similar view of the same spring assembled when at the extreme limit 65 of its movement. Fig. 5 shows a similar view of the unassembled parts of another form of my spring. Fig. 6 shows a similar view of the unassembled parts of still another form of my spring. Fig. 7 shows a 70 similar view of the parts shown in Fig. 6 after being assembled. Fig. 8 shows still another form of the spring when the parts are unassembled. Fig. 9 shows a similar view of the same parts shown in Fig. 8 75 having the several parts partially assembled. Fig. 10 shows still another form of my spring with the parts assembled.

Referring more particularly now to my Figs. 1, 2, 3, and 4: 1 represents a semi-rigid 80 spring member preferably of U-shape. The central part of this semi-rigid member is substantially rigid while the arms 1' and 1² are capable of a slight bending when subjected to a great strain. 2 is an elastic loop 85 member which is adapted to be connected to the arm 1² by means of a link 3 or other suitable pivoted means and it is likewise adapted to be connected to the arm 1' by the link 4 or other suitable pivoted connecting means. 5 is a bridge connecting member shown in dotted outlines in Fig. 1 and in full outlines in Figs. 2, 3 and 4. This bridge connecting member is adapted to be locked with a loop of the elastic loop member by 90 means of a link 6 pivotally mounted on the bridge connecting member and the elastic loop member and it is also adapted to be locked with another loop of the elastic loop member by means of a link 7 pivotally 100 mounted on the said bridge connecting member and another loop of the said elastic loop member 2.

My spring having been assembled after the manner just described it may be connected with the axle 8 of the vehicle as clearly shown in Figs. 2, 3 and 4. This is the preferable way of mounting my spring upon a vehicle but it will be apparent that my spring is also adapted to be mounted 110

upon a vehicle so that the semi-rigid member 1 comes in contact with the axle 8 instead of the bridge connecting member 5 in which case the bridge connecting member 5 would be connected with the body of the vehicle.

The several parts shown in Fig. 1 are shown while in their normal position not under strain of any kind, and they are in that condition when manufactured and ready to be assembled. It will be noted that in Fig. 2 the semi-rigid member 1 has been drawn inwardly a small distance and further that the loops of the elastic loop member 2 which are united to the bridge connecting member 5 by the links 6 and 7, are drawn upwardly toward said bridge connecting member 5 a small distance. When the three several parts of my spring are assembled as described, they are as clearly shown in Fig. 2 under an elastic strain so that the arms 1' and 1² are slightly drawn inwardly and the tension of those arms when connected by the links 3 and 4 of the elastic loop member 2 tends to draw outwardly the loops of the elastic loop member 2 which are connected by the links 6 and 7 to the bridge connecting member 5. Thus both the arms of the semi-rigid member 1 and the elastic loop member 2 are placed under an elastic strain when the parts of the spring are assembled.

Fig. 2 shows the position of my spring before it is placed under the tare weight of the load.

Fig. 3 shows my spring after it has been subjected to a load which has carried it to such a position that when further load is added its resistance will increase in a substantially geometrical progression. Ordinarily the position shown in Fig. 3 will be reached after the spring has been subjected to the tare weight of a load and in addition thereto the maximum varying load which may be carried by it. The further possible movement of the spring toward the position shown in Fig. 4 is provided for the purpose of absorbing shocks or other unusual disturbances received by the vehicle and preferably the spring is so constructed that the bridge connecting member 5 and the semi-rigid member 1 will never come in contact no matter how great the load or how violent the shock or disturbance affecting the spring action.

For the purpose of showing the character of the spring resistance which I provide in my spring it may be assumed for example that the spring resisting force offered by the spring when traveling from the position shown in Fig. 2 to the position shown in Fig. 3 would be, say, one thousand pounds while the resisting power offered by the spring to travel from the position shown in Fig. 3 to the position shown in Fig. 4 would

be, say, eight thousand pounds or eight times as much. Of course the amount of resisting power of the spring is always under regulation of the manufacturer thereof and can be regulated as the necessities 70 may require.

The elastic loop member 2 bends very readily as compared with the bending qualities of the arms 1' and 1² of the semi-rigid member 1. When the parts are in the position shown in Fig. 2 it will be noted that the links 6 and 7 are turned inward toward the axle 8 and thereby obtain a great leverage upon the sections 2' of the elastic loop member which lies between the said links 6 and 7 and the said arms 1' and 1². This leverage of the links 6 and 7 tends to draw inwardly the said arms 1' and 1² of the semi-rigid member 1.

When the spring parts have assumed the position shown in Fig. 3 it will be noted that the links 6 and 7 have been drawn outwardly away from the axle 8 and their leverage is thus reduced so that the section 2' tends to be drawn outwardly by the tension of the arms 1' and 1² of the semi-rigid member 1 and these latter mentioned arms then assume almost the same position as that shown in Fig. 1.

When the spring parts have assumed the position shown in Fig. 4 it will be noted that the links 6 and 7 have been drawn so far outwardly away from the axle 8 that they again assume a position practically in a straight line with the line of the sections 100 2' and when in that position they tend to pull the arms 1' and 1² inwardly into a position substantially like that shown by the said arms in Fig. 2.

The leverage created by the position of 105 the links 6 and 7 and the sections of the elastic loop member to which they are connected through the sections 2' upon the arms 1' and 1² when in the position shown in Fig. 2, is a very even leverage and it 110 will be noted that the arms 1' and 1² are bent practically throughout their entire length as shown by the dotted lines. The leverage of the same parts when they are in the position shown in Fig. 4 however is 115 a much stronger leverage and it is exerted upon the arms 1' and 1² at a much sharper angle and therefore requires a considerably greater power to force the parts to the position shown in Fig. 4.

Referring now to Fig. 5 it will be noted that both the semi-rigid member 1 and the bridge connecting member 5 are substantially identical with the corresponding members shown in Figs. 1, 2, 3 and 4 while the 125 elastic loop member 9 shown in Fig. 5 is of a somewhat different conformation than the elastic loop member 2 shown in Figs. 1, 2, 3 and 4. In an elastic loop member such as that represented by 9 I am able to em- 130

ploy a greater length of material and so arrange the loops of the material that the parts when subjected to an elastic strain under load will not interfere with each other. In 5 this conformation a very heavy material may be used and at the same time the amount of space occupied by the spring need not be greater than that occupied by an elastic loop section of a conformation like that 10 shown at 2. It may be noted however that the responsive action of the spring when placed under a load will be substantially like that of the elastic loop member 2. Of course it will be understood that the semi-rigid member 1, the bridge connecting member 5 and the elastic loop member 9 as shown 15 in Fig. 5 may be united by exactly the same means employed in substantially the same way as those illustrated in Figs. 2, 3 and 4.

20 In the spring represented in Fig. 6 the semi-rigid member 1 having the arms 1' and 1² is substantially the same as the corresponding member in the other figures previously described but in this figure I have 25 made it somewhat lighter in weight than that shown in the other figures. The elastic loop member 10 of Fig. 6 is lighter than the corresponding members 2 and 9 of the first five figures and it is proportionally lighter 30 than the corresponding members 2 and 9 of those figures in proportion to the difference in size between the semi-rigid member 1 of the several figures just described and the semi-rigid member 1 of this Fig. 6. The 35 elastic loop member 10 is much shorter than the corresponding members 2 and 9 and is designed for use where the spring is subjected to a much less tare weight than the springs of the other figures would be adapted 40 to resist. Obviously the several parts of the spring shown in Fig. 6 can be connected by identically the same means as those shown in Figs. 2, 3 and 4, and in Fig. 7 these parts are shown as so connected and assembled.

45 By comparing Figs. 1 and 6 it will be noted that the space between the ends of the elastic loop member 2 and the arms 1' and 1² is much greater than the corresponding difference between the ends of the elastic 50 loop member 10 and the arms 1' and 1² shown in Fig. 6. By comparing Fig. 2 with Fig. 7 it will be noted that the angles of the links 6 and 7 relative to the axle 8 are much less in Fig. 2 than are the corresponding angles of those parts in Fig. 1.

55 Inasmuch as the character of the progressive resistance of my spring is determined by the relative position of the links 6 and 7 and the parts connected thereto, it will be evident that the links 6 and 7 used in the construction shown in Fig. 7 will reach a position similar to that shown by the same links in Fig. 3 much more quickly than the same parts will in the construction shown in 60 Fig. 3. It follows from the above that the

spring resisting power of that form of my spring shown in Fig. 7 changes from a substantially arithmetical progression to a substantially geometrical progression at a much earlier period of travel of the parts of the 70 spring than is the case with the parts shown in Figs. 1, 2, 3 and 4.

From the foregoing it will be evident that I am able by the method of arranging the parts of my spring to control in any desired way the characteristic resisting power 75 of my spring through any part of its movement.

Referring now to Fig. 8 it will be noted that the elastic loop member 2 is identical 80 with the elastic loop member shown in Figs. 1, 2, 3 and 4 and that the bridge connecting member 5 shown in dotted outline in Fig. 8 is likewise like that marked 5 shown in dotted outline in Fig. 1. The semi-rigid member 11 differs from the corresponding member 1 shown in the other figures previously described in that it is made regulatable as to the spread of its arms 11' and 11². This regulating means I will now describe. 90 The part 11 is made up of the arms 11' and 11² and the central rigid member 11³. The arms 11' and 11² are rigidly secured to the rigid member 11³ by bolts 14, 15, 16 and 17, the bolts passing through slots 95 14', 15', 16' and 17' in the arms 11' and 11² and being rigidly secured to the rigid member 11³. The rigid member 11³ (which would usually correspond to the rigid frame of the car) carries depending 100 lugs 18 and 19 through which set-screws 12 and 13 pass; the ends of said set-screws resting against the ends of the arms 11' and 11². When it is desired to alter the spread of the arms 11' and 11², the bolts 14, 15, 16 and 17 are loosened and the set-screws 12 and 13 are moved away from the ends of the arms 11' and 11². The said arms may then be moved either inwardly or outwardly according to the position from which they 110 start, the limit of movement being governed by the length of the slots 14', 15', 16' and 17'. Obviously any change in the spread of the arms 11' and 11² will alter the distance 115 between the ends of these arms and the ends of the elastic loop member 2 so that when the parts are assembled as shown in Fig. 9 the tension of the arms 11' and 11² and the elastic loop member 2 will be regulated 120 by the spread of the arms and it is for the purpose of governing this initial tension of the said several parts that I provide these regulating means. Another advantage resulting from this construction is that I am able to regulate such tension of the spring 125 even during the time when the spring is carrying a load.

In Fig. 9 I have shown the parts shown in Fig. 8 assembled except that the links 3 and 4 are shown in this figure as broken to indi- 130

cate the above described regulatable tension. It will be noted that the parts shown in this figure are assembled by the same connecting means as those used in Figs. 2, 3 and 4 and it will be obvious that the several parts act when they are subjected to a load in substantially the same manner as do the corresponding parts shown in Figs. 2, 3 and 4.

10 In Fig. 10 I have shown another modification of my invention and in that figure, 20 represents a rigid member which is preferably coincident with the rigid frame of the car to which my spring is applied. To the rigid member 20 I adjustably secure arms 22 and 21 and connected with these arms is a spring resisting part 23. The means for regulating the spread of the arms 21 and 22 as shown in my Fig. 10 are substantially the same as the corresponding means for such regulation shown in Figs. 8 and 9 and I have marked the same with numbers which correspond thereto. It will be obvious to those skilled in the art that in the suggested construction shown in Fig. 10 I may employ two arms each of them having the same conformation as the arm 22 or I may employ two arms each of them having the same conformation as that marked 21 and that the spring so formed will act in substantially the same way when subjected to a load as will the construction shown in Fig. 10 where the arms 21 and 22 are of unlike conformation. It will be clear from the foregoing description of my invention that in the construction shown in Fig. 10 the spring will respond at first through a small distance of its travel with a resistance which acts in a progression which is substantially arithmetical and through the rest of its travel it will act with a resistance which is substantially geometrical. Obviously the spring would rest upon an axle applied to what is practically the central part of the spring resisting part 23. Further it will be clear that the semi-rigid part 20 as shown in Fig. 10 and the spring arms 21 and 22 may be so combined and arranged with the spring resisting member 23 that under the tare weight of a load this spring will offer a resistance to the same which increases in a progression which is substantially geometrical.

Obviously the spring loop members 2 and 9 when under the weight of a load act to resist the weight of said load with forces varying according to their construction and this characteristic is likewise true of the spring resisting member 23 shown in Fig. 10. Bearing this in mind I have in my claims referred in some of them to the members 2 and 9 and member 23 as spring resisting members.

While I have shown my invention as adapted particularly for use with motor ve-

hicles it will be evident that it is likewise adapted for use in many other ways or to almost any form of vehicle and I do not wish to confine myself to the particular adaptations herein shown and described. 70

Having thus described my invention what I claim is:

1. A compound spring comprising a semi-rigid member, an elastic loop member, a bridge connecting member, means for connecting said elastic loop member and said bridge connecting member and additional connecting means between said elastic loop member and said semi-rigid member whereby when said spring is subjected to the tare 80 weight of a load and the weight of an additional variable load it will offer a resistance to the same which increases in a progression which is substantially arithmetical and when subjected to an additional load or strain it 85 will offer a resistance thereto which will increase in a progression which is substantially geometrical.

2. A compound spring comprising a semi-rigid member, an elastic loop member, a bridge connecting member and means for connecting said elastic loop member and said bridge connecting member and additional connecting means between said elastic loop member and said semi-rigid member whereby when said spring is subjected to the tare 90 weight of a load it will offer a resistance to the same which increases in a progression which is substantially arithmetical and when subjected to an additional load or strain it 95 will offer a resistance thereto which will increase in a progression which is substantially geometrical.

3. A compound spring comprising a semi-rigid member, an elastic loop member, said semi-rigid member having a central portion which is substantially rigid and being provided with an arm at each end which is capable of slight bending when subjected to a great strain, a bridge connecting member, 110 means for adjustably uniting said members whereby they may be initially placed under an elastic strain and means for uniting said elastic loop member and said bridge connecting member so that they are placed under an initial elastic strain.

4. A compound spring comprising a semi-rigid member, an elastic loop member, a bridge connecting member, means for connecting said elastic loop member and said bridge connecting member, and additional connecting means between said elastic loop member and said semi-rigid member, said semi-rigid member having a central portion which is substantially rigid and being provided with an arm at each end which is capable of slight bending when subjected to a great strain.

5. A compound spring comprising a semi-rigid member, an elastic loop member, a

bridge connecting member, means for connecting said elastic member and said bridge connecting member, and additional connecting means between said elastic loop member and said semi-rigid member, said semi-rigid member being U-shaped and having a central portion which is substantially rigid and being provided with an arm at each end which is capable of slight bending when subjected to a great strain.

5 6. A compound spring comprising a semi-rigid member, an elastic loop member, a bridge connecting member, links connecting said elastic loop member with said semi-rigid member and links connecting said elastic loop member with said bridge connecting member.

10 7. A compound spring comprising a semi-rigid member, an elastic loop member, a bridge connecting member, means for connecting said elastic loop member and said bridge connecting member, and additional means between said elastic loop member and said semi-rigid member, said semi-rigid member having a central portion which is

substantially rigid and being provided with a regulatable arm at each end which is capable of slight bending when subjected to a great strain.

8. A compound spring comprising a semi-rigid member, an elastic loop member, a bridge connecting member, said semi-rigid member having a central portion which is substantially rigid and being provided with an arm at each end which is capable of 35 slight bending when subjected to a great strain, means for connecting said elastic loop member and said bridge connecting member and means for adjustably uniting the arms of said semi-rigid member with 40 said elastic loop member, whereby the said parts may be initially placed under an elastic strain.

In witness whereof I have hereunto set my hand in the presence of two witnesses.
